(57) **CLAIM**

The ornamental design for a sonar transducer array housing, as shown and described.

DESCRIPTION

FIG. 1 is a first perspective view of a sonar transducer array housing showing the new design;

FIG. 2 is a second perspective view thereof, shown in a first environmental use;

FIG. 3 is a third perspective view thereof, shown in a second environmental use;

FIG. 4 is a fourth perspective view thereof, shown in a third environmental use;

FIG. 5 is a fifth perspective view thereof, shown in a fourth environmental use; and,

FIG. 6 is a sixth perspective view thereof, shown in a fifth environmental use.

The dash-dash broken lines illustrate environmental structure and form no part of the claimed design.
